AIR COOLING APPARATUS

Frederick L. Shelor, Richmond, Va., assignor to
 S. and S. Engineering Company, Richmond,
 Va., a corporation of Virginia

Application January 18, 1933, Serial No. 652,388

3 Claims. (Cl. 261—107)

The invention relates to new and useful improvements in an air cooling apparatus which may be used for cooling the temperature of a room.

5 In my co-pending application, Serial No. 649,997, filed January 3, 1933, there is shown and described an apparatus for cooling the air of a room wherein a fibrous material is saturated with water and an air current is caused to pass over the surface of the saturated material for vaporizing the water. The latent heat incident to the vaporization of the water cools the air and surfaces with which the water contacts, and the cooled air passing from the apparatus is circulated through the room.

10 The present invention has to do with an improvement in an arrangement of the saturated fabric, and has for its object the increasing of the efficiency of the cooling apparatus.

15 A further object of the invention is to provide an apparatus of the above type wherein the saturated fabric is so arranged that the air currents pass through the fabric and thereby the dust particles suspended in the air current are filtered out and collect on the fabric.

20 A still further object of the invention is to provide an air cooling apparatus wherein the fabric is supplied with water in such a way that when the air current ceases and the apparatus is rendered inoperative, there will be no objectionable dripping of water from the apparatus.

25 These and other objects will in part be obvious, and will in part be hereinafter more fully disclosed.

30 In the drawing, which shows by way of illustration, one embodiment of the invention;

Figure 1 is a plan view of an apparatus embodying the invention with parts of the cover broken away to show the inner structure.

35 Figure 2 is a view partly in side elevation and partly in section through the apparatus.

40 In carrying out the invention a casing is provided which is closed, except for an air inlet port and an air outlet port. Within the casing is an air circulating fan which operates to draw air into the intake port and forcibly eject the air through an outlet port. Extending across the air passage between the inlet and outlet port is a fabric through which the air is forced by the air impelling means. This fabric is saturated with water so that the air, as it passes through the fabric contacting with the water globules clinging to the fabric, will vaporize the same. The heat incident to the changing of the water into the form of vapor is taken from the air and

the fabric parts cooling the air and cooling the fabric, and the fabric will in turn further cool the air through the contact therewith. Thus the air passing through the outlet has been lowered in temperature, and this will efficiently lower the temperature of the room in which the apparatus is operated.

45 Referring more in detail to the drawing, the apparatus as illustrated consists of a supporting base 1 carrying a standard 2 on which is mounted a casing consisting of a receptacle 3. The bottom of the receptacle is provided with an opening 4 as shown in the drawing, and this opening is closed by a plate 5 which may be secured thereto by suitable bolts 6, 6. The standard 2 extends through the plate 5, and a motor indicated at M is mounted on the standard. This motor may be of any desired construction and has only been indicated diagrammatically. Extending upwardly from the bottom of the receptacle 3 is a 50 partition 7. This partition is soldered or otherwise secured to the bottom and extends preferably substantially to the same height as the side walls 3a of the receptacle. A side wall of the receptacle at the upper end thereof is flanged and beaded as indicated at 8 for strengthening the same. The partition 7 is provided with an angular portion 9 for strengthening said partition and for providing a ledge which overhangs and partially closes an annular chamber 10. This 55 chamber is liquid-tight and is supplied with water, preferably to the water line level indicated by the broken line. The side wall 3 of the receptacle is provided with a series of bracket arms 11 which project above the upper edge of the receptacle. A screen is attached to the arms and completely encircles the receptacle and extends all the way from the top edge of the receptacle to the upper ends of the arms. Each arm has an inwardly extending portion formed with a 60 U-shaped recess in the free end thereof. A wire 13 has a fabric 14 attached thereto, and this wire is adapted to be placed in the recess in the arms 11. The fabric hangs from the wire and extends down into the receptacle beneath the water line. This fabric will be saturated with water through capillary attraction. There is a horizontal partition wall 15 located above the motor M, and the motor shaft extends above said horizontal partition and carries at its upper end an 65 air impeller 16. This air impeller 16 consists of a lower disk 17 and an upper annular member 18 parallel therewith. The opening in the annular member is centrally thereof. The upper annular member is mounted on radial partitions 19. 70

75 The upper annular member is mounted on radial partitions 19. 75

80 The upper annular member is mounted on radial partitions 19. 80

85 The upper annular member is mounted on radial partitions 19. 85

90 The upper annular member is mounted on radial partitions 19. 90

95 The upper annular member is mounted on radial partitions 19. 95

100 The upper annular member is mounted on radial partitions 19. 100

105 The upper annular member is mounted on radial partitions 19. 105

As shown in the drawing there are six of these radial partitions, and between the partitions are radial passage-ways 20.

Above the air impeller is a cover 21 which rests on the wire 13. Said cover has a depending annular member 22 which is located inside of the wire and the upper edge of the fabric portion. This cover overhangs the screen 12. The cover has an opening 23 centrally therethrough in which is located a screen 24.

When the motor is connected to a proper source of power the impeller 16 is rotated, and as the impeller rotates air will be drawn in through the central opening of the cover and will be forcibly discharged through the radial passages 20. This will cause the air current set up by the impeller to impinge upon the fabric, and as the fabric retards the free movement of the air therethrough the air will travel with the impeller following around the inner surface of the fabric, thus setting up a travelling air current which strikes the fabric and finally finds its way through the fabric. In other words, the fabric restricts the passage of the air so that a pressure is developed in the chamber directly within the fabric which aids in the passing of the air through the fabric. This together with the travelling of the air current with the rotating impeller in a circular direction across the inner face of the fabric greatly aids in the vaporization of the water saturating the fabric. As the air passes through the fabric, any dirt or dust carried thereby is filtered out and collects on the fabric. The air passing through the fabric gives up its heat to the water as it is changed to vapor form. This cools the fabric, and the fabric in turn further cools the air so that the air issuing through the screen will be filtered, free from suspended dust, and will also be cooled. The cool air circulating through the room cools the room, and the vapor carried in suspension in the air will condition the area so that it is free from excessive dryness. While the air enters through a relatively small intake port it passes out through a relatively large outlet port, and thus creates free and easy movement in the air about the apparatus which is free from any excessive draft or air currents in any particular direction.

Inasmuch as the fabric is supplied with water by capillary attraction, when the impeller is stopped and the apparatus rendered inoperative, the water in the fabric, if there is any drip at all, will pass back into the water receptacle. Water may be readily supplied in any suitable way to this receptacle.

It will be understood, of course, that the construction may be greatly varied from that shown in the drawing which is merely illustrative of one form which the invention may take. The essential feature of the invention resides in the placing of the fabric so that it extends across the path of travel of the air from the inlet to the outlet of the apparatus, thus requiring the air to pass through the fabric. While the impeller is shown as placed within the apparatus it will be understood that it may be otherwise disposed, so long as an air current is created which causes the air of the room to pass through the apparatus and also pass through the fabric which is saturated with water. It is preferred, however, to use an air impeller of the type shown which will not only cause the air to impinge at all points

against the inner face of the cylindrical fabric wall, but also to travel in a circular path within the receptacle and across the inner face of the fabric during the rotation of the impeller.

It will be apparent that the cooling apparatus described above is in the form of a unit which may be made very small, and which may be readily transferred from one portion to another, or placed on a desk. It may be effectively used in place of an ordinary fan for circulating air and cooling the same in a portion of a room where one is working. On the other hand, it may be made in a larger unit and used for cooling the entire room if desired. It is understood also that this unit may be made in other forms, and the form described in detail is purely for the purpose of illustrating the invention and one of its uses.

Having thus described the invention, what I claim as new and desire to secure by Letters Patent, is:-

1. An air cooler including in combination a standard, a receptacle mounted thereon, said receptacle having a partition forming an annular chamber for retaining water, bracket arms carried by the receptacle and projecting above the same, a cylindrical fabric member supported by said bracket members and extending into the receptacle beneath the water level, a cover for said receptacle contacting with said fabric at the upper edge thereof, an impeller within the receptacle movable about a vertical axis and having radial air passages therein, said cover having an air inlet whereby air is directed into the center of the impeller and forcibly ejected therefrom against the fabric along the surface of the fabric and through the fabric.

2. An air cooler including in combination a standard, a receptacle mounted thereon, said receptacle having a partition forming an annular chamber for retaining water, bracket arms carried by the receptacle and projecting above the same, a cylindrical fabric member supported by said bracket members and extending into the receptacle beneath the water level, a cover for said receptacle contacting with said fabric at the upper edge thereof, an impeller within the receptacle movable about a vertical axis and having radial air passages therein, said cover having an air inlet whereby air is directed into the center of the impeller and forcibly ejected therefrom against the fabric along the surface of the fabric and through the fabric, said cover being placed about the outer wall of the receptacle so as to provide an outlet port all the way around the receptacle.

3. An air cooler including in combination, a standard, a receptacle mounted thereon, said receptacle having a partition forming an annular chamber for retaining water, a cylindrical fabric member extending into the receptacle beneath the water level forming a fabric wall, means for supporting said fabric member, a closure for said receptacle contacting with the upper edge of the fabric wall and spaced from the upper edge of said receptacle to form an outlet therefor, said closure having an opening centrally thereof, and means for forcibly causing the current of air to flow into the casing through said inlet, through the fabric wall in the casing, and from the casing through the outlet.

FREDERICK L. SHELOR.
